UNITED STATES PATENT OFFICE.

IRA J. OWEN, OF GRAND RAPIDS, MICHIGAN, ASSIGNOR TO BISSELL CARPET SWEEPER COMPANY, OF GRAND RAPIDS, MICHIGAN.

CARPET SWEEPER.

Application filed May 6, 1924. Serial No. 711,360.

This invention relates to improvements in carpet sweepers. It relates more particularly to improvements in the shell or case for a carpet sweeper.

5 The object of the invention is to provide a light strong casing making use of flexible board such as composition board or plywood for the shell of the casing.

10 Objects pertaining to details and economies of construction of my invention will definitely appear from the detailed description to follow.

15 I accomplish the objects of my invention by the devices and means described in the following specification. The invention is clearly defined and pointed out in the claims.

20 A structure which is a preferred embodiment of my invention is clearly illustrated in the accompanying drawing forming a part of this application, in which:

Fig. I is a perspective view of my improved carpet sweeper case, the sweeper parts being absent.

25 Fig. II is an enlarged detail transverse sectional elevation through the case.

Fig. III is an enlarged detail section showing the connection of the ply-wood or composition board to the side rail.

30 Fig. IV is a detail view of the joints between the side and end parts taken on section line 4—4 of Fig. I.

Fig. V is an enlarged detail cross sectional view taken on line 5—5 of Fig. IV, the end being omitted.

35 In the drawing similar reference numerals indicate similar parts in all of the views.

The parts of the drawing will be referred to by their reference numbers. The shell 1 is made of fiber board, composition board, 40 or thin flexible ply-wood having quarter-cylindrical curved sides 2 and 3 at front and rear, respectively. The ends 4 are of wood or other suitable material perforated and notched to accommodate the working parts 45 of the carpet sweeper.

Side rails 5 are provided connecting the square ends of the ends 4 together. These contain longitudinal grooves 6 to receive and

stiffen the edges of the shell 1. The end pieces are gained or notched at 7 into the side pieces 5 as indicated by dotted lines in Fig. II.

Reinforce fillet blocks 8 are along the top edge inside of each end to reinforce and strengthen the connection between the shell 55 and the ends. The ends are cut at an oblique angle at 9 and a supporting block 10 supports each corner of the shell which is extended at 11 beyond the end 4. This affords a broad support and attachment for 60 the shell and strengthens the extension thereof, which, with the extended ends of the side bars, affords support for the guard bar of the carpet sweeper.

From this description it will be seen that 65 my improved construction of case lends itself to a very cheap design of carpet sweeper case when fiber board, sheet metal or heavy pasteboard may be made use of for the shell, because the edges are confined and supported and a broad attaching surface is provided. Such a structure is durable and avoids the metallic rattle of a metallic case.

Because of the curved conformation, the shell itself, owing to its intimate connection 75 to the other part, adds to the rigidity of the structure which is a matter of considerable importance in the maintenance of the working parts in their most effective relation. The ease of operation of the carpet 80 sweeper is greatly enhanced by such perfect support.

Having thus described my invention what I claim as new and desire to secure by Letters Patent is:

85 1. In a case for carpet sweepers, case ends curved on their upper edges, in combination with a suitable shell formed of flexible board with its front and rear curved in the arc of a circle and extended at each corner beyond said ends, side bars coterminous with said shell grooved on their tops to receive and retain the vertical edges of said shell, the said case ends gained into the said side bars, and supporting blocks at each corner of the 90 case interposed between the shell and ends 95

conformed and secured to the inner surfaces of said shell and secured to said ends, for the purpose specified.

2. In a case for carpet sweepers, case ends curved on their upper edges, in combination with a suitable shell formed of flexible board with its front and rear curved in the arc of a circle, and side bars coterminous with said shell grooved on their tops to receive and

retain the vertical edges of said shell, the 10 said case ends gained into the said side bars to the inner face of said groove whereby the side bars securely retain the said shell against the said ends, for the purpose specified.

In witness whereof I have hereunto set my hand.

IRA J. OWEN.
